C. L. JOHNSTON

ILLUMINATED SUITCASE

Filed March 7, 1924

Attorney

UNITED STATES PATENT OFFICE.

CHALMERS L. JOHNSTON, OF BRIDGEPORT, NEBRASKA.

ILLUMINATED SUITCASE.

Application filed March 7, 1924. Serial No. 697,586.

To all whom it may concern:

Be it known that I, CHALMERS L. JOHNSTON, a citizen of the United States, residing at Bridgeport, in the county of Morrill, State of Nebraska, have invented a new and useful Illuminated Suitcase; and I do hereby declare the following to be a full, clear, and exact description of the invention, such as will enable others skilled in the art 10 to which it appertains to make and use the same.

The invention relates to suit cases, and has for its object to provide a suit case with means whereby, when the suit case is opened, 15 an electric lamp therein may be lighted, thereby illuminating the contents thereof, and rendering it relatively easy to locate articles in the suit case.

A further object is to provide one end of 20 the suit case with an electric lamp controllable from adjacent the handle of the suit case, thereby allowing the pavement in front of the carrier of the suit case to be illuminated when desired. Also to provide 25 shutter means for protecting said electric lamp.

With the above and other objects in view the invention resides in the combination and arrangement of parts as hereinafter set 30 forth, shown in the drawing, described and claimed, it being understood that changes in the precise embodiment of the invention may be made within the scope of what is claimed without departing from the spirit 35 of the invention.

In the drawing:—

Figure 1 is a perspective view of a conventional form of suit case, showing the lights applied thereto.

Figure 2 is a diagrammatic view of the circuit.

Figure 3 is a detail sectional view through one end of the suit case and the light carried thereby.

Figure 4 is an enlarged front elevation of the light carried by the end of the suit case.

Referring to the drawing, the numeral 1 designates a conventional form of suit case, 50 which suit case is formed from sections 2 of conventional construction, which are hinged together at 3. The upper side of one of the suit case sections 2 is provided with a handle member 4 adapted 55 to be grasped by the operator when carry-

ing a suit case from place to place. It has been found that when a suit case is opened, especially in a dark room or dark place, it is hard to locate small articles therein. To obviate this difficulty the inner side of 60 one of the sections 2 of the suit case is provided with an electric lamp 4, which lamp is in circuit with the battery 5 through the wires 6, and which circuit may be opened and closed by the slidable switch 7 65 when it is desired to light the lamp 4 and illuminate the interior of the suit case.

One end of one of the sections 2 of the suit case is provided with an opening 8, in which is disposed a flanged ring 9, and 70 between which flanged ring 9 and the reflector 10, the lens 11 is disposed and held by the dished member 12, which is engaged by an annular retaining member 13. Secured to the outer side of the flanged ring 10 by 75 means of the securing bolts 14, which extend through the ring 9 and the retaining ring 13, is an annular member 15, the lower side of which is provided with an ear 16, through which the lower securing bolt 14 80 passes, and the upper side with an ear 17, through which the pivotal bolts 18 of the segmentally shaped guard plates 19 extend. Plates 19 are disposed between the ring 15 and the flanged ring 9, and when in open 85 position allow the passage of light rays from the electric lamp 20, in a manner whereby light may be reflected on the sidewalk ahead of the person, while walking. The lamp is obscured from view, and the 90 lens 11 protected when the guard plates 19 are in closed position as shown in Figure 4. The lamp 20 is in circuit with the battery 5 through the wires 21, and switches 22 and 23, and when the switch 23 is closed within 95 the suit case, it will be seen that a person carrying the suit case by the handle 4 may easily and quickly light or extinguish the lamp 20 by manipulating the switch 22. However by providing the switch 23 within 100 the suit case, it is obvious that the circuit controlling the lamp 20 may be permanently broken within the suit case in a manner whereby it can not be controlled by the switch 22, thereby preventing unauthorized persons from illuminating the lamp 20 and running down the battery.

From the above it will be seen that illuminating means is provided for the interior of the suit case, and for projecting 110

rays of light forwardly of the suit case when being carried. It will also be seen that a control switch is provided adjacent the handle of the suit case where it may be 5 easily manipulated by the finger of the person carrying the suit case, and the circuit may be broken inside the suit case for preventing unauthorized persons from manipulating or lighting the lamp carried at 10 the forward end of the suit case.

The invention having been set forth what is claimed as new and useful is:—

1. The combination with a suit case wall having an annular opening therein, an 15 annular flanged ring disposed in said opening, a lens disposed in said opening, a dished reflector disposed in said opening and engaging the lens, a lamp carried by the reflector, a dished casing disposed on the 20 rear side of the reflector, an annular flanged ring secured to the inner side of the wall of the suit case and engaging the casing, segmentally shaped plates pivoted adjacent one 25 of their corners and normally closing the opening in the wall and a ring secured to

the wall outside thereof and behind which the segmentally shaped plates are disposed.

2. The combination with a suit case wall having an annular opening therein, an 30 annular flanged member disposed in said opening, a lens disposed in said opening, a dished reflector engaging the lens, a lamp carried by said reflector, a casing disposed on the rear side of the reflector, an annular flanged ring secured to the inner side of the 35 wall and engaging the casing, segmentally shaped plates pivoted adjacent one of their corners and normally closing the opening in the wall outside of the wall and a ring spaced from the outer side of the wall and 40 between which ring and the wall the segmentally shaped plates are disposed and are movable.

In testimony whereof I have signed my name to this specification in the presence of 45 two subscribing witnesses.

CHALMERS L. JOHNSTON.
